WILLIAM M. SCOTT, OF TREDYFFRIN TOWNSHIP, CHESTER COUNTY, PENNSYLVANIA.

ELECTRICAL SWITCHING SYSTEM.

1,353,185.

Specification of Letters Patent. Patented Sept. 21, 1920.

Application filed September 6, 1918. Serial No. 252,817.

To all whom it may concern:

Be it known that I, WILLIAM M. SCOTT, a citizen of the United States, residing in Tredyffrin township, in the county of Chester and State of Pennsylvania, have invented a new and useful Electrical Switching System, of which the following is a specification.

My invention relates to an electrical switching system comprising a source of current and a consumption circuit or translating device protected against reversal of polarity or voltage, no voltage and excess current.

My invention resides in a system of the character referred to, particularly when the translating device is of the electrolytic type, such as may be employed in the production of oxygen and hydrogen by electrolysis, wherein the protective means comprise automatic circuit breaker mechanism responsive to reversal of polarity or voltage, no voltage or excess current; and more particularly in such a system wherein a double arm circuit breaker is tripped or controlled by electro-magnetic tripping means responsive to reversal of polarity or voltage, no voltage and excess current, the windings of the no voltage and polarity reversal tripping means being serially connected.

For an illustration of one of the forms my invention may take reference is had to the accompanying drawings, in which—

Figure 1 is a front elevational view of circuit breaker structure.

Fig. 2 is a side elevational view of the same.

Fig. 3 is a fragmentary side elevational view, on enlarged scale, of part of the mechanism shown in Fig. 2.

Fig. 4 is an end elevational view of the structure shown in Fig. 3.

Fig. 5 is a side elevational view, on larger scale, of polarity reversal tripping mechanism of Figs. 1 and 2.

Fig. 6 is an end elevational view of the structure shown in Fig. 5.

Fig. 7 is a bottom plan view of the structure shown in Fig. 5.

Fig. 8 is a diagrammatic view of one of various circuit arrangements of a system embodying my invention.

Referring to Figs. 1 and 2, the circuit breaker structure comprises two circuit breaker arms A and B constituting a so-called "double arm" circuit breaker having independently movable arms with means

for locking each arm and means for tripping either or both arms.

The circuit breaker arm A comprises the main terminal blocks 1 and 2 disposed upon a suitable insulating base 3 and adapted to be bridged by the laminated contact 4 carried by the arm 5 pivoted to the base at 6 and actuated by a toggle comprising the links 7 and 8, the latter having the operating handle 9 carrying the latch roller 10 engaged by the latch 11 to hold the bridging member 4 in circuit closing position. The latch 11 is pivoted to the base or housing at 12, the latch 11, as viewed in Figs. 2 and 3, tending to move in a counter-clockwise direction under the influence of the spring 13, Fig. 4. Pivoted concentrically with the latch 11 is a latch actuator 14 having the rearwardly extending tail 15 disposed in the path of travel of the member 16 actuated by the armature 17, pivoted at 18, said armature being that of an overload tripping device comprising a U-shaped iron member 19 embracing a lead to the terminal block 2.

To the latch actuator 14 is secured a structure 20 on whose upper side is adapted to engage the surface 21 of the cam member 22 independently pivoted at 12 and having the downwardly extending portion 23 carrying the lug 24 loosely engaging in the forked end 25 of the member 26 secured to the armature 27 pivoted at 28. The armature 27 is normally close to the poles 29 of the no-voltage or low-voltage tripping coil 30, the usual plunger 31 pressed outwardly by the spring 32 being provided to shift the armature 27 in a counter-clockwise direction upon its pivot 28 upon loss or decrease of voltage, causing the surface 21 of member 22 to depress latch actuator 14 and so depress latch 11 to trip the breaker. This no-voltage magnet effects a direct tripping of the breaker.

The cam member 22 is engaged on its surface 22a by roller 10a, concentric with and to one side of roller 10, when the breaker is closed to restore armature 27 to the poles of the no-voltage magnet, which if energized will retain the armature and allow the breaker to be latched.

At 33 is indicated a switch which is closed when the breaker arm A is closed and which is opened when that arm moves to open circuit position, the switch 33 being suitably insulated in well known manner.

The arm B is in many respects similar in structure to arm A and comprises the upper

main terminal 34, and lower main terminal 35, see Fig. 8, with which co-operates a bridging contact 36 similar to movable contact member 4, similarly mounted and actuated by a toggle. The operating handle 9^a of the arm B is restrained in circuit closing position by latch 11^a, actuated by latch actuator 14^a, these parts being similar to those described in connection with arm A.

10 The latch actuators 14 and 14^a of arms A and B, respectively, are positively mechanically connected by the transversely extending bars or shafts 37, 37 with suitable intervening insulations 38, so that when either 15 latch actuator is moved both are moved or actuated.

Associated with the arm B is a tripping device responsive to reversal of voltage or polarity, as distinguished from reversal of 20 current. This tripping device comprises the arm 39, pivoted at 40, and having the horizontally extending portion 41 secured at 42 to the latch actuator 14^a, thus in effect being mechanically connected to the transversely 25 extending bars 37, 37. Adapted to actuate the member 39 in clockwise direction, as viewed in Fig. 5, is the lug 43 upon the armature structure 44 comprising the side members 45 and 46, each consisting of a 30 laminated permanent magnet, these side members having the connecting yoke 47, the armature structure as a whole being pivoted at 48, 48. The forward ends of the permanent magnets 45 and 46 are of opposite polarity, the forward end of magnet 45 being, 35 for example, a south pole, as indicated by S; the north pole of permanent magnet 46 is indicated at N.

Disposed above and below the armature 40 structure are the horizontally extending cores 49 and 50 of electro-magnets whose windings are indicated respectively at 51 and 52. The coils 51, 52 and 30 are connected in series with each other, as indicated in 45 Fig. 8, the coils 51 and 52 being wound in such direction or so connected that for normal proper polarity conditions the poles of the upper magnet 51 are similar to and therefore oppose the adjacent poles N and S 50 of the permanent magnet armature system, while the poles of the lower electro-magnet 52 are of opposite polarity to the adjacent armature poles and therefore normally attract the armature downwardly, the downward movement being limited by the stop 53. Thus normally the pole of the magnet 51 55 above the pole N of the armature structure, is a north pole, while its other pole will be a south pole adjacent the south pole S of the armature structure; and of the lower magnet 52 the pole adjacent the pole N of the armature structure is normally a south pole, while its other pole is a north pole.

Referring now to Fig. 8, G is any suitable 60 source of current, as for example, a

dynamo-electric generator which may be of the compound wound type. The generator is connected by conductors 54 and 55 with the double pole switch 56, which when closed with the contacts 57 and 58 places the source 70 G in communication with the distribution or consumption circuit. The source G is adapted to supply current to any current consuming device, and particularly to electrolytic cells E, which may be employed for producing oxygen and hydrogen by electrolysis and in connection with which it is of great importance that the polarity of the system be never reversed, lest hydrogen be produced at the pole which was formerly producing 80 oxygen, and therefore produce a dangerous explosive mixture.

The contact 58 communicates through conductor 59 and the overload tripping device of the arm A, diagrammatically indicated at 60, with the lower terminal 2 of the arm A and through the bridging member 4 to the upper terminal 1, which connects with one terminal of the cells E. The switch terminal 57 communicates through conductor 90 61 with the lower terminal 35 of the circuit breaker arm B, and thence through the bridging member 36 to the upper terminal 34, which is connected with the other terminal of the cells E.

The no-voltage coil 30 and the polarity reversal coils 51 and 52 are connected in series with each other through the switch 33 between the conductor leading from the upper terminal 1 of the arm A and the conductor 100 54 connected to the generator G.

The operation is as follows:

With the switch 56 closed, the generator G having a given terminal of proper polarity and other conditions normal, current will 105 pass from the generator G through the conductors 59 and 61, the circuit breaker arms A and B and through the translating or consumption device E. When the consumption device is an electrolytic cell or cells, the current passing therethrough will produce oxygen at one pole and hydrogen at the other, the two gases being taken off separately. Should, however, the current be passed through the cell or cells in reverse direction, 110 oxygen will be produced at the pole at which hydrogen should be produced, and similarly at the other pole hydrogen will be produced where oxygen should be produced, with the result that the gases taken off at both poles 115 will produce with those previously taken off mixtures of hydrogen and oxygen, which are dangerous in the sense that they are explosive and readily ignited.

Such an electrolytic device is to some 120 extent at least a storage battery capable of discharging a current if the voltage impressed upon the circuit, as by generator G, falls below the voltage of the device E. For example, if the generator G were at 130

rest and the switch 56 left closed, the residual magnetism of the field of the generator G might readily be reversed by discharge from the device E, with the result 5 that when the generator was again started up, its polarity would be reversed and such as to pass current through the electrolytic device E in reverse direction, with the resultant above-described undesirable mixture 10 of gases. To prevent this mishance and to anticipate flow of current in wrong direction, the tripping mechanism comprising the coils 51 and 52 and the no-voltage magnet 30 are provided. So long as the polarity 15 of the generator G is normal or correct, the armature structure 44 will be held against the stop 53, due both to gravity and the pull exerted by the lower electro-magnet 52, and the repulsion of the upper electro-magnet 20 51. Should, however, the polarity be reversed, the current through the magnet windings 51 and 52 will be reversed, with the result that the lower electro-magnet 52 will repel the armature structure and the 25 upper electro-magnet 51 will attract it, with the result that the armature structure 44 will rotate in a counter-clockwise direction, as viewed in Fig. 5, and cause the member 43 to engage the member 39 and so actuate 30 latches 11 and 11^a of both circuit breaker arms A and B, and so trip both or either of them.

With the breaker arms A and B both open, and upon closure of the switch 56, arm A is first closed, thereby establishing the circuit through the coils 30, 51 and 52. If the polarity of the generator G has been reversed, the breaker arm A will be tripped immediately the operator removes his hand 40 from the operating lever 9, because the latch 11 of arm A will be tripped through the members 37 connected to the member 39, which is actuated by the armature structure 44. If it should be attempted to close 45 arm B before closing arm A, the same will not latch because the circuit of the coil 30 is open at switch 33, arm A being open, and the spring 32 will hold the armature 27 of the no-voltage tripping coil away from 50 its poles and thereby hold the latch 11^a, through the interconnecting members 37, in opposition to its spring similar to spring 13, from taking a locking position.

If either switch 56 or switch 33 is open, 55 the no-voltage coil 30 cannot be energized, and neither arm A nor arm B can be latched in circuit closing position because the armature 27 will not be held attracted, but will be held by spring 32 in position to hold 60 latches 11 and 11^a from locking their respective operating handles 9 and 9^a.

It is of importance that the no-voltage tripping coil 30 be connected in series with the tripping device comprising the coils 51 65 and 52, in order that should there be a rup-

ture in either winding 51 or 52, the no-voltage or low-voltage tripping mechanism comprising the coil 30 will prevent closure of either or both arms A or B, whether or not a reversal of polarity has occurred. 70 And obviously, if a break should occur in the coil 30 or anywhere in the circuit of the coils 30, 51 or 52, or if in general a low-voltage or no-voltage condition should obtain, both breaker arms A and B will be 75 tripped if both have been closed, and if either or both have been open will prevent closure of both.

And obviously the overload tripping mechanism, which may be associated with 80 either arm A, as illustrated, or with arm B, or with both, will trip both arms A and B upon occurrence of excess current flow or upon abnormal conditions in the circuit which upon closure of the breakers A and 85 B would cause excess of current flow, will cause either arm to be tripped when it is attempted to close the other.

What I claim is:

1. The combination with a source of 90 current and a translating device, of circuit breaker mechanism intervening between them and comprising independently operable switches each having means for restraining the same in normal position, and 95 means responsive to reversal of polarity or voltage for actuating said restraining means.

2. The combination with a source of 100 current and a translating device, of circuit breaker mechanism intervening between them and comprising independently operable switches each having means for restraining the same in normal position, means responsive to reversal of polarity or voltage for actuating said restraining means, and a 105 no-voltage tripping magnet for actuating said restraining means.

3. The combination with a source of 110 current and a translating device, of circuit breaker mechanism intervening between them and comprising independently operable switches each having means for restraining the same in normal position, and electro-magnetic tripping means responsive to reversal of polarity or voltage for actuating 115 said restraining means comprising a member polarized independently of the circuit of said source of current and translating device and a winding in which the direction of current reverses with reversal of polarity 120 or voltage.

4. The combination with a source of 125 current and a translating device, of circuit breaker mechanism intervening between them and comprising independently operable switches each having means for restraining the same in normal position, electro-magnetic tripping means responsive to reversal of polarity or voltage for actuating said restraining means comprising a mem- 130

ber polarized independently of the circuit of said source of current and translating device and a winding in which the direction of current reverses with reversal of polarity 5 or voltage, and a no-voltage tripping magnet for actuating said restraining means and having its winding connected in series with said winding.

5. The combination with a source of 10 current and a translating device, of circuit breaker mechanism intervening between them and comprising independently operable switches each having means for restraining the same in normal position, and 15 tripping means responsive to reversal of polarity or voltage for actuating said restraining means comprising a permanently polarized armature structure and coöperating electro-magnet structure having a 20 winding in which the direction of current reverses upon reversal of polarity or voltage.

6. The combination with a source of current, of an electrolytic gas generator supplied thereby, circuit breaker mechanism intervening between said source and said generator and comprising independently operable switches each having means for restraining it in closed position, and electro-magnetic means responsive to reversal of 30 polarity or voltage for preventing closure of said circuit breaker mechanism.

7. The combination with a source of current, of an electrolytic gas generator supplied thereby, circuit breaker mechanism intervening between said source and said generator and comprising independently operable switches each having means for locking it in circuit closing position, electro-magnetic means responsive to reversal of 35 polarity or voltage for preventing closure of said circuit breaker mechanism, and means comprising a no-voltage tripping magnet preventing closure of said breaker except when said magnet is energized.

45. 8. The combination with a source of current, of an electrolytic gas generator supplied thereby, circuit breaker mechanism intervening between said source and said generator and comprising independently operable switches each having means for locking it in circuit closing position, electro-magnetic means responsive to reversal of 50 polarity or voltage controlling said circuit breaker mechanism, and a no-voltage tripping magnet controlling said breaker, the windings of said no-voltage tripping magnet and said electro-magnetic means being connected in series with each other.

9. The combination with a source of current, of an electrolytic gas generator supplied thereby, a switch intervening between them, a circuit breaker intervening between them and comprising independently operable switches each having means for locking 60 it in closed position, and electro-magnetic

means responsive to reversal of polarity or voltage for preventing closure of said circuit breaker.

10. The combination with a source of current, of an electrolytic gas generator supplied thereby, a switch intervening between them, a circuit breaker intervening between them and comprising independently operable switches each having means for locking it in closed position, electro-magnetic means responsive to reversal of polarity or voltage for preventing closure of said circuit breaker, a no-voltage tripping magnet controlling said circuit breaker, and a switch movable with one of said switches controlling the 70 circuit of the windings of said electro-magnetic means and said no-voltage tripping magnet. 80

11. The combination with a source of current and a translating device, of circuit breaker mechanism intervening between them and comprising independently operable switches each having means for restraining the same in normal position, electro-magnetic tripping means responsive to reversal of polarity or voltage for actuating 85 said restraining means comprising a member polarized independently of the circuit of said source of current and translating device and a winding in which the direction of current reverses with reversal of polarity or 90 voltage, a no-voltage tripping magnet for actuating said restraining means and having its winding connected in series with said winding, and a switch controlling the circuit of said windings and movable with one 95 of said independently operable switches.

12. The combination with a source of current, of an electrolytic gas generator supplied thereby, circuit breaker mechanism intervening between them and comprising independently operable switches each having means for locking it in closing position, electro-magnetic means responsive to reversal of 100 polarity or voltage preventing closure of said circuit breaker mechanism, a no-voltage tripping magnet preventing closure of said circuit breaker mechanism except when said magnet is energized, the windings of said no-voltage tripping magnet and of 105 said electro-magnetic means being connected in series, and a switch movable with one of said independently operable switches closing the circuit of said windings when said one of said independently operable switches is moved to circuit closing position. 110

13. The combination with a source of current, of an electrolytic gas generator supplied thereby, circuit breaker mechanism intervening between them and comprising independently operable switches each having 115 means for locking it in closing position, electro-magnetic means responsive to reversal of polarity or voltage preventing closure of said circuit breaker mechanism, a no-voltage tripping magnet preventing clo- 120

125

130

sure of said circuit breaker mechanism except when said magnet is energized, the windings of said no-voltage tripping magnet and of said electro-magnetic means being connected in series, a switch movable with one of said independently operable switches closing the circuit of said windings when said one of said independently operable switches is moved to circuit closing position, and manually operable switching mechanism in series with said circuit breaker mechanism between said source of current and said gas generator.

14. The combination with a source of current and electrolytic means supplied thereby, of circuit breaker mechanism intervening between them and comprising independently operable switches each having means for restraining it in normal position, said switches disposed, respectively, in sides of the circuit of opposite polarities, and electro-magnetic means responsive to reversal of polarity or voltage operating upon said restraining means to prevent switch restraint upon switch movement to circuit closing position during polarity reversal.

15. The combination with a source of current and electrolytic means supplied thereby, of circuit breaker mechanism intervening between them and comprising independently operable switches each having means for restraining it in normal position, said switches disposed, respectively, in sides of the circuit of opposite polarities, electro-magnetic means responsive to reversal of polarity or voltage operating upon said restraining means to prevent switch restraint upon switch movement to circuit closing position during polarity reversal, and means responsive to low or no voltage preventing switch restraint upon switch movement to circuit closing position during low or no-voltage conditions.

16. The combination with a source of current and electrolytic means supplied thereby, of circuit breaker mechanism intervening between them and comprising independently operable switches each having means for restraining it in normal position, said switches disposed, respectively, in sides of the circuit of opposite polarities, electro-magnetic means responsive to reversal of polarity or voltage operating upon said restraining means to prevent switch restraint upon switch movement to circuit closing position in unison with one of said independently operable switches.

sition during polarity reversal, and means in series with said electro-magnetic means and responsive to low or no voltage preventing switch restraint upon switch movement to circuit closing position during low or no-voltage conditions.

17. The combination with a source of current and electrolytic means supplied thereby, of circuit breaker mechanism intervening between them and comprising independently operable switches each having means for restraining it in normal position, said switches disposed, respectively, in sides of the circuit of opposite polarities, electro-magnetic means responsive to reversal of polarity or voltage operating upon said restraining means to prevent switch restraint upon switch movement to circuit closing position during polarity reversal, means responsive to low or no-voltage preventing switch restraint upon switch movement to circuit closing position during low or no-voltage conditions, and a switch controlling the circuit of said electro-responsive means and said means responsive to low or no voltage, said switch taking circuit closing position in unison with one of said independently operable switches.

18. The combination with a source of current and electrolytic means supplied thereby, of circuit breaker mechanism intervening between them and comprising independently operable switches each having means for restraining it in normal position, said switches disposed, respectively, in sides of the circuit of opposite polarities, electro-magnetic means responsive to reversal of polarity or voltage operating upon said restraining means to prevent switch restraint upon switch movement in circuit closing position during polarity reversal, means in series with said electro-magnetic means and responsive to low or no voltage preventing switch restraint upon switch movement to circuit closing position during low or no-voltage conditions, and a switch controlling the circuit of said electro-responsive means and said means responsive to low or no voltage, said switch taking circuit closing position in unison with one of said independently operable switches.

In testimony whereof I have hereunto affixed my signature this 3rd day of September, 1918.

WILLIAM M. SCOTT.
